UNITED STATES PATENT OFFICE.

HOWARD B. SHERMAN, OF BATTLE CREEK, MICHIGAN, ASSIGNOR TO CONSOLIDATED PRESS COMPANY, OF HASTINGS, MICHIGAN, A CORPORATION OF MICHIGAN.

MACHINE FRAME AND BASE.

1,251,430.

Specification of Letters Patent. Patented Dec. 25, 1917.

Application filed June 25, 1917. Serial No. 176,929.

To all whom it may concern:

Be it known that I, HOWARD B. SHERMAN, a citizen of the United States, residing at Battle Creek, in the county of Calhoun and 5 State of Michigan, have invented certain new and useful Improvements in Machine Frames and Bases; and I hereby declare that the following is a full, clear, and exact description thereof, reference being had to 10 the accompanying drawings, which form part of this specification.

This invention is an improvement in bases and frames for heavy machines, such as drawing presses and the like, and it has particular reference to the novel construction 15 of the base of such presses.

The object of the invention is to provide a very strong machine frame having a base which will be practically free from pockets 20 and places where dirt and rubbish may accumulate, and which will have a symmetrical massive finished appearance.

I will explain the invention with reference to the accompanying drawings which 25 illustrate one practical embodiment of the invention and will enable others to adapt and use the same for various machines, and summarize in the claims the features and constructions of parts for which protection 30 is desired.

In the drawings:

Figure 1 is a side elevation of the complete frame.

Fig. 2 is a front view thereof.

35 Fig. 3 is a transverse section on the line 3—3 Fig. 2.

Fig. 4 is a bottom plan view of the base.

Fig. 5 is a detail section on line 5—5 Fig. 1.

40 The frame as shown is composed of a base member 1, side members or housings 2, and a crown or top member 3.

The base member 1 is approximately H-shaped in plan view, and has a body portion 45 1^b having depending side flanges 1^c; at each end of this body portion are leg members 1^f which are preferably angular or tapered, viewed from the sides of the frame, (see Fig. 1) being wider at bottom than at top.

50 These legs are hollow, and the outer end walls 1^d of the body also form the outer end walls of the adjacent legs; such legs having inner walls 1^e and outer side walls 1^f. The side walls 1^f connect the walls 1^d 55 and 1^e and cover the space between said

walls and prevent any dirt or rubbish dropping between the walls 1^d and 1^e and collecting in the legs.

The walls 1^e of the body merge into the walls 1^e of the legs so that viewed from below (see Fig. 4) the base is hollow, but viewed from above (see Fig. 3) the base appears solid; and viewed from the side or end the base also appears solid (see Figs. 1 and 2).

On the lower end and outer face of each leg is a boss 1^g which is bored for the passage of the usual hold-down bolts (not shown) by which the frame is rigidly fastened to a foundation. These bosses are 60 cast on the outer extremity of each leg at the lower end thereof and are easily accessible; whereas in the ordinary type of frames the legs are hollow and the securing bolts are arranged between the side walls of the 65 legs, which are open on their outer surfaces and being open form pockets which permit the accumulation of dust and dirt; and access to the nuts on the fastening bolts in such construction is troublesome. In my 70 base while the legs are hollow, they present externally solid appearances and no pockets are formed for dust, etc., to collect and the anchor bolts engaging bosses 1^g are always 75 readily accessible.

80 Openings are formed in the top of the base adjacent the corners thereof for the passage of tie-bolts 4 hereinafter referred to, and these openings are surrounded on their lower ends by sleeves or housings 1^h 85 which are formed integral with the base, all the parts of the base being cast integral so as to make it strong and solid. Viewed from the top, side or front the base presents a massive solid appearance, but viewed from 90 below, as indicated in Fig. 4, it is hollow.

95 The side members 2 of the frame while presenting a solid appearance are preferably cast hollow, as shown, but the side walls thereof are united and braced by an internal centrally disposed vertical partition 2^a 100 (Fig. 3). The upper and lower ends of these pieces may have transverse openings as at 2^b to give clearance, rendering the side frames approximately H-shaped in appearance. In the side walls of the lower openings 2^b, see Figs. 1 and 5, are apertures 2^v 105 which permit access to the tie rods 4, to enable the rods to be heated with a torch or other suitable means, in the event of the 110

frame having to be taken apart for any reason after the tie rods have been shrunk in place. In the event of the slide becoming stuck on a dead center due to the operator placing more than one blank in the dies the rods can be heated and expand until the crank can be turned past the center, then the rods are allowed to cool and shrink to place. The lower openings 2^b permit feeding stock right to left in the press in addition to front and back. The upper ends of the side members 2 are shown as provided with lower halves 2^e, of bearings for the bushings of the journals of the main shaft 15 of the machine, (not shown).

The side members 2 may be provided with ribs 2ⁱ on the lower ends engaging corresponding grooves 1ⁱ on the top of the base to prevent lateral movement of the side 20 members on the base. Transverse movement of the side members on the base may be prevented by keys 5 engaging corresponding grooves in the lower end of the side members and top of the base as indicated in 25 Fig. 1.

The crown or top member 3 is adapted to rest upon and connect the upper ends of the side members 2 and is arch-shaped, viewed from the side, and is preferably hollow, but 30 presents externally a solid appearance; its ends are provided with half-bearing members 3^e which are complementary to the half-bearing members 2^e on the side frames so that when the frame is assembled the parts 35 2^e and 3^e together form bearings or housings for the bushings of the bearings of the main shaft of the machine.

Relative movement of the top and side members may be prevented by means of ribs 40 3^k on the top member engaging grooves 2^k on the upper ends of the side members; and transverse movement of the crown relative to the side members may be prevented by having the half-bearings 2^e rabbeted to the 45 upper ends of the members 2 as indicated at 2^e in Fig. 1.

The crown or top member 3 is also provided at its ends with internal integral sleeves or housings 3^a for the passage of the 50 tie-bolts 4, by which the members of the frame are braced together.

As shown four tie-bolts are employed, two at each side of the machine; and these tie-bolts extend through the sleeves 1^b in the 55 base upward through the side members 2 and through the sleeves 3^a on the crown member, and may be secured both above and below by nuts 4^b, 4^c in the usual manner.

The tie-rods are preferably shrunk into 60 place. When the machine is assembled the rods are heated and the nuts on the rods tightened while the rods are hot and when the rods cool their shrinkage will further tighten the tie-rods and bind the members 65 of the frame rigidly together.

A frame constructed as illustrated in the drawings is very substantial and is solid in appearance and capable of standing any desired strain.

The principal feature of this frame is the 70 base so constructed that while it is actually hollow and light it presents a solid appearance, is thoroughly braced in all directions, contains no pockets for the accumulation or collection of rubbish or dirt, and the bosses 75 for the anchor-bolts are readily accessible.

What I claim is:

1. A machine base composed of a hollow body portion having projecting hollow legs tapered outwardly from top toward the bottom, said legs being open on the inside and presenting a solid appearance externally, the walls of the legs uniting with the end and side walls of the base, substantially as described. 80

2. A machine base composed of a hollow body portion having projecting hollow legs tapered outwardly from top toward the bottom, said legs being open on the inside but closed externally, the walls of the legs uniting with the end and side walls of the base, said base being approximately H-shaped in plan, and each of said legs having an exterior boss at its lower end for engagement of an anchor-bolt. 90

3. A machine base, comprising a hollow body portion having outwardly projecting hollow legs at each corner, said legs being open on their inner sides and closed on their outer sides and tapered outwardly from top to bottom, the end walls of the legs uniting with the end and side walls of the base, substantially as described. 95

4. A machine base, comprising a hollow body portion having outwardly projecting hollow legs at each corner, said legs being open on their inner sides and closed on their outer sides and tapered outwardly from top to bottom, the end walls of the legs uniting with the end and side walls of the base, said base being approximately H-shaped in plan, and each of its legs having an external boss at its lower end for engagement of the anchor-bolts. 100

5. A machine base composed of a hollow body portion having projecting hollow legs tapered outwardly from top toward the bottom, said legs being open on the inside and presenting a solid appearance externally, the walls of the legs uniting with the end and side walls of the base, and said base having integral sleeves adjacent the upper end of each leg for the engagement of tie-bolts, said sleeves being concealed within the base. 115

6. A machine base, comprising a hollow body portion having outwardly projecting hollow legs at each corner, said legs being open on their inner sides, the end and side walls of the legs uniting with the end and side 120 130

walls of the base, and each of its legs having an external boss at its lower end for engagement of the anchor-bolts, said base having integral sleeves adjacent the upper end of 5 each leg for the engagement of the tie-bolts, said sleeves being within the base.

7. A machine base composed of a hollow body portion having projecting hollow legs tapered outwardly from top toward the bottom, said legs being open on the inside, the end and walls of the legs uniting with the end and side walls of the base, each of said legs having an exterior boss at its lower end for engagement of an anchor-bolt, and said 10 base having integral sleeves adjacent the upper end of each leg for the engagement of tie-bolts, said sleeves being concealed within the base.

8. For a machine frame, a hollow side member having a vertically disposed partition integral therewith, and transverse openings adjacent its ends, substantially as described.

9. For a frame, a hollow side member having a vertically disposed partition integral therewith, and a half-bearing for the shaft journal at its upper end, substantially as described.

10. For a frame, a hollow side member having internal vertically disposed members or partitions integral therewith, and transverse openings adjacent its ends and with a half-bearing for the journal of the shaft at its upper end, substantially as described.

11. For a machine frame, an arched hollow top member having internal integral sleeves at its ends for the passage of fastening bolts.

12. A machine frame comprising a base composed of a hollow body portion having projecting legs tapered outwardly from top toward the bottom and open on the inside, the end walls of the legs uniting with the end and side walls of the base; side members each having an internal vertically disposed partition integral therewith, and an arched top member provided with internal integral sleeves at its ends; and tie-bolts extending through the side members and engaging the sleeves in the top and base members, substantially as described.

13. A machine frame comprising a base member composed of a hollow body portion having outwardly projecting legs, said legs being open on their inner sides, the side walls of the legs uniting with the front and rear walls of the base, and each leg having an external boss at its lower end for engagement of the anchor-bolts; side members each having an internal vertically disposed partition integral therewith, and a half-bearing for a shaft journal at its upper end; and an arched top member provided with integral sleeves at each end for the passage of the

bolts; and tie-bolts extending through the side members and engaging the sleeves in the top and base members, substantially as described.

14. A machine frame comprising a base member composed of a hollow body portion having outwardly projecting hollow legs at each corner, said legs being open on their inner sides, the side walls of the legs uniting with the front and rear walls of the base, 70 said base being approximately H-shaped in plan; and each leg having an external boss at its lower end for engagement of the anchor-bolts; side members each having an internal vertically disposed partition integral therewith, transverse openings adjacent its ends, and a half-bearing for a shaft journal at its upper end; and an arched top member provided with internal integral sleeves at each end for the passage of the 75 bolts; and tie-bolts extending through the side members and engaging the sleeves in the top and base members, substantially as described.

15. For a press frame, a hollow side member having a transverse opening in its lower end and apertures in the side walls of said opening to permit access to the tie-rods, substantially as described.

16. For a press frame, a hollow side member having internal vertically disposed members or partitions integral therewith, a transverse opening in its lower end and apertures in the side walls of said opening to permit access to the tie-rods, substantially 95 as described.

17. For a press frame, a hollow side member having internal vertically disposed members or partitions integral therewith, a transverse opening in its lower end and 105 apertures in the side walls of said opening to permit access to the tie-rods, and a half-bearing for a shaft journal at its upper end, substantially as described.

18. A machine frame comprising a base having a hollow body portion with projecting legs tapered outwardly from top toward the bottom and open on the inside, the end walls of the legs uniting with the end and side walls of the base; side members each 110 having a transverse opening in its lower end and apertures in the side walls of said openings to permit access to the tie-rods; a top member; and tie-bolts extending through the side members and engaging the 115 top and base members, substantially as described.

19. A machine frame comprising a base having a hollow body portion with projecting legs tapered outwardly from top toward the bottom and open on the inside, the end walls of the legs uniting with the end and side walls of the base; side members each 120 having an internal vertically disposed partition integral therewith and a transverse 125

opening in its lower end and apertures in the side walls of said opening to permit access to the tie-rods; a top member provided with internal integral sleeves at its ends; 5 and tie-bolts extending through the side members and engaging the top and base members, substantially as described.

Copies of this patent may be obtained for five cents each, by addressing the "Commissioner of Patents, Washington, D. C."

In testimony that I claim the foregoing as my own, I affix my signature in presence of two witnesses.
